CONVERSION OF HYDROCARBON OILS

John B. Barnes, Chicago, Ill., assignor to Universal Oil Products Company, Chicago, Ill., a corporation of Delaware

Application April 6, 1935, Serial No. 15,017

4 Claims. (Cl. 196—48)

This invention particularly refers to an improved process for the selective conversion of relatively low boiling and relatively high boiling hydrocarbon oils under independently controlled conversion conditions of elevated temperature and superatmospheric pressure in separate heating coils wherein the liquid conversion products are subjected to vaporization at substantially reduced pressure relative to that at which they are formed, the resulting non-vaporous residual liquid subjected to coking assisted by commingling therewith, in the coking zone, regulated portions of the highly heated products from the light oil heating coil of the system and wherein the light distillate product of the process, preferably comprising materials of high anti-knock value within the boiling range of gasoline, are subjected to stabilization and the normally gaseous products of the process subjected to absorption, hydrocarbon oil charging stock for the process being utilized as an absorption medium for said gases and the enriched charging stock supplied to a fractionator wherein it is subjected, together with the vaporous conversion products of the process, including those from the coking operation, to fractionation for the recovery of fractionated vapors, from which said light distillate and gas are recovered, and for the formation of intermediate liquid conversion products comprising said relatively low boiling and high boiling oils which are subjected to said conversion.

One of the features of the present invention comprises separation of the hydrocarbon oil charging stock for the process and the intermediate liquid conversion products of the process (reflux condensate) recovered by fractionation of the vaporous conversion products into selected relatively low boiling and high boiling fractions and subjecting said relatively low boiling and high boiling fractions each to independently controlled conversion conditions of elevated temperature and superatmospheric pressure each in a separate heating coil of the same cracking system.

Another feature of the invention resides in the use of a furnace, for heating of the high boiling fractions of the charging stock and reflux condensate, of what is known as the "double-end-fired" type, wherein, in the present invention, two separate substantially equal streams of said relatively high boiling oil are simultaneously subjected to substantially the same heating conditions and thereby each is subjected to substantially identical conversion conditions of elevated temperature, superatmospheric pressure and conversion time, the two highly heated streams issu-

ing from separate similar sections of the heating coil of the furnace being commingled and supplied to subsequent portions of the system.

Another feature of the invention resides in the use of another furnace of the "double-end-fired" type wherein the relatively low boiling fractions of the charging stock and reflux condensate are heated to the desired conversion temperature in a centrally located fluid heating section and in one combustion zone of the furnace and then subjected to what is ordinarily termed "soaking" under independently controlled heating conditions in the other combustion zone of the furnace whereby the oil is maintained at a substantially constant relatively high conversion temperature for a predetermined time.

Another feature of the invention comprises the use of highly heated products from the light oil heating coil of the system as a means of assisting reduction of the flashed residue from the vaporizing chamber of the cracking system to substantially dry coke by commingling said residual liquid with regulated quantities of said highly heated products in alternately operated relatively low pressure coking chambers. Any remaining portion of said highly heated products from the light oil heating coil, not required as a heat carrying medium for the coking operation, is supplied to the same high pressure reaction chamber to which the highly heated products from the heavy oil heating coil of the system are supplied and the vaporous products from the coking zone are returned to the same vaporizing chamber to which liquid and vaporous products from the reaction chamber are supplied and from which the non-vaporous residual liquid subjected to said coking is derived.

Another feature of the present invention resides in the use of regulated quantities of the relatively high boiling fractions of the charging stock and reflux condensate as a heating medium for reboiling the light distillate product of the process in the stabilization stage of the system. The high boiling fractions of the reflux condensate and charging stock employed in this manner are thereby cooled and, in the preferred embodiment of the present invention, are then returned to the fractionator of the system to serve as a cooling and refluxing medium in this zone.

Another special feature of the invention comprises the use of hydrocarbon oil charging stock for the process as an absorber oil for removing high boiling components, including propane, butane and their homologs, as well as any higher boiling materials, from the normally gaseous

conversion products of the process, the enriched charging stock being supplied from the absorption step to the fractionator of the system.

I am aware that many of the features of the present process are not in themselves new with the present invention but the invention is not based upon the individual features per se but depends upon the novel and advantageous manner in which the individual features are combined. 10 in a single unified process in which they are interdependent and in which they mutually contribute to produce the desired final results. It will be understood, however, that the invention is not limited to the use, in combination, of all of 15 the features above mentioned and/or subsequently described but is limited only as necessitated by the prior art and defined in the appended claims.

In one embodiment, the invention comprises subjecting an oil of relatively high boiling characteristics to conversion conditions of elevated temperature and superatmospheric pressure in a heating coil and communicating reaction chamber, withdrawing both vaporous and liquid conversion products from the reaction chamber in 25 commingled state and introducing the same into a reduced pressure vaporizing chamber wherein separation of vapors and residual liquid conversion products is accomplished, withdrawing the latter from the vaporizing chamber and introducing the same into alternately operated coking chambers wherein their reduction to substantially dry coke is accomplished, returning vaporous products from the coking chambers to the vaporizing chamber, subjecting vaporous products 30 from the vaporizing chamber to fractionation, whereby their insufficiently converted components boiling above the range of the desired final light distillate product of the process are condensed as reflux condensate and separated into selected 35 relatively low boiling and high boiling fractions, subjecting fractionated vapors of the desired end boiling point to condensation, collecting and separating the resulting distillate and uncondensed gases, subjecting said gases to absorption by contacting the same with hydrocarbon oil charging stock for the process, supplying the enriched charging stock from the absorption step to said fractionating step wherein it commingles with the vaporous conversion products of the process and is subjected to separation together with the reflux condensate into selected relatively low boiling and high boiling fractions, returning said high boiling fractions of the charging stock and reflux condensate to the heating coil for further conversion, subjecting said low boiling fractions of the charging stock and reflux condensate to independently controlled conversion conditions of elevated temperature and superatmospheric pressure in a separate heating coil, introducing regulated quantities of the highly heated products from the last mentioned heating coil into the coking chamber to supply heat thereto and assist reduction of the residual liquid conversion products to coke, supplying any remaining portion of the highly heated products from the last mentioned heating coil to said reaction chamber, subjecting said distillate recovered by condensation of the fractionated vaporous conversion products to stabilization to substantially free the 70 same of any excessive quantities of undesirable low boiling components and dissolved gases, supplying heat for said stabilization step by indirect heat exchange between the distillate resulting 75 from said stabilization and regulated quantities

of said relatively high boiling fractions of the charging stock and reflux condensate from the fractionator whereby to reboil said distillate, cooling the resulting stabilized and reboiled distillate by indirect heat exchange with the distillate supplied to the stabilization step, whereby to preheat the latter, and removing said cooled stabilized distillate from the system as the final motor fuel product of the process. 5

The accompanying diagrammatic drawing illustrates one specific form of apparatus in which the process of the invention may be accomplished.

Referring to the drawing, furnace 1 comprises the relatively heavy oil heating zone of the system to which relatively high boiling fractions of the intermediate liquid conversion products (reflux condensate) and charging stock are supplied, as will be later more fully described, and wherein the oil is heated to the desired conversion temperature. The furnace here illustrated is what is generally known as a "double-end-fired" type of furnace having separate combustion and heating zones 2 and 3 and a centrally located fluid heating zone 4. Controlled amounts of combustible fuel and air are independently supplied to each of the combustion and heating zones 2 and 3 through suitable firing tunnels indicated at 5 on opposite ends of the furnace and the hot combustion gases from each of the combustion and heating zones 2 and 3 pass over the respective bridge walls 6 and 7, are commingled in the central portion of the furnace and pass downward through fluid heating zone 4 to flue 8 and thence to a suitable stack (not shown). The fluid conduit through which the relatively high boiling oil supplied to furnace 1 is passed is divided, in the case here illustrated, into two substantially equal sections, one of which comprises the right hand half of tube bank 9 located within fluid heating zone 4, tube bank 10 located adjacent the roof of combustion and heating zone 3 and tube bank 11 located adjacent the floor of combustion and heating zone 3 while the other section comprises the left hand side of tube bank 9, tube bank 12 located adjacent the roof of combustion and heating zone 2 and tube bank 13 located adjacent the floor of combustion and heating zone 2. By maintaining substantially equal firing conditions in combustion and heating zones 2 and 3 and by passing substantially equal amounts of the relatively heavy oil in two continuous streams through the two sections of the fluid conduit all of the oil is subjected to substantially equal heating conditions and the drop in pressure due to friction through the furnace is greatly reduced as compared with that which would result from passing the total oil through the entire fluid conduit. The two streams of highly heated fluids are discharged, in the case here illustrated, from tube banks 11 and 13 through the respective lines 14 and 15, commingle in line 16 and are directed through valve 17 in this line into reaction chamber 18 wherein they are preferably sprayed against the inner surface of the walls of the chamber by means of a suitable spray or spreader-flange arrangement such as indicated at 19, although any other method of introducing this material into the reaction chamber at any desired point in this zone may be employed. 40

Chamber 18 is preferably maintained at a substantial superatmospheric pressure which may be substantially the same or somewhat lower than that employed at the outlet from the heating coil. The reaction chamber is preferably well insu- 45 50 55 60 65 70 75 80 85 90 95 100

lated, although not indicated in the drawing, in order to prevent the excessive loss of heat therefrom by radiation so that the heated products supplied to this zone and particularly their vaporous components are subjected therein to appreciable continued conversion. In the case here illustrated, both vaporous and liquid conversion products are withdrawn in commingled state from the lower portion of chamber 18 through line 20 and valve 21 and are introduced into vaporizing chamber 22.

Chamber 22 is preferably maintained at a substantially reduced pressure relative to that employed in the reaction chamber and the liquid conversion products supplied to this zone are subjected therein to further vaporization. Residual liquid conversion products remaining unvaporized in chamber 22 are withdrawn from the lower portion of this zone through line 23 and valve 24 to pump 25 by means of which they are fed through line 26 and are introduced by means of the respective lines 28 and 28', controlled respectively by valves 29 and 29', into coking chambers 30 and 30' wherein they are reduced to substantially dry coke.

Furnace 31 comprising the light oil heating zone of the system is also, in the case here illustrated, a furnace of the double-end-fired type having independently fired combustion and heating zones 32 and 33 and a centrally located fluid heating zone 34. Controlled amounts of combustible fuel and air are independently supplied to each of the combustion and heating zones 32 and 33 by means of suitable firing tunnels indicated at 35 located at opposite ends of the furnace and the combustion gases from both combustion and heating zones 32 and 33 pass over the respective bridge walls 36 and 37 and are directed downward in commingled state through fluid heating zone 34 to flue 38 and thence to a suitable stack (not shown). In the case here illustrated, relatively low boiling oils from within the system are supplied, as will be later more fully described, to that portion of the fluid conduit located within fluid heating zone 34 and thence pass successively through tube bank 40 located adjacent the floor of combustion and heating zone 32, tube bank 41 located adjacent the roof of the furnace and tube bank 42 located adjacent the floor of combustion and heating zone 33. With this flow through the furnace independent control is exerted over the heating conditions and the temperature to which the oil is subjected in the portions of the fluid conduit located in the two combustion and heating zones 32 and 33. Preferably, the oil is heated to or near the desired maximum conversion temperature in passing through tube banks 39, 40 and the left hand portion of tube bank 41 and then is maintained for a predetermined time at a substantially constant temperature near that previously attained as it passes through the right hand portion of tube bank 41 and tube bank 42. The highly heated stream of relatively low boiling oil is discharged from tube bank 42 through line 43 and a regulated portion or all of this material is directed through line 44 and through the respective lines 45 and 45', controlled, respectively, by valves 46 and 46', into coking chambers 30 and 30' wherein they commingle with the materials undergoing coking in this zone and serve to assist the coking operation or a portion or all of the highly heated products from furnace 31 supplied to the coking zone may be introduced thereto by means of line 47 and valve

48 whereby they commingle in lines 28 and 28' with the residual liquid supplied to the coking zone from vaporizing chamber 22.

Any remaining portion of the highly heated products from furnace 31 not required as a heat-carrying medium for assisting the coking operation may be directed from line 43 through line 49 and valve 50 into reaction chamber 18 wherein they are subjected to continued conversion together with the heated products from heating coil 4, serving to heat the latter and particularly the vaporous components thereof to a somewhat higher conversion temperature to increase their conversion and being themselves partially cooled by contact with the cooler products from furnace 1 whereby conversion of the more highly heated products from furnace 31 is retarded.

Coking chambers 30 and 30' are similar zones preferably operated at substantially atmospheric or a relatively low superatmospheric pressure which is preferably somewhat higher than that employed in the vaporizing chamber in order to avoid the use of a pump or compressor for returning the vaporous products from the coking chamber to the vaporizing chamber. It will be understood, of course, that one or any desired number of a plurality of coking chambers may be employed although two are illustrated in the drawing and when a plurality is employed the chambers may be simultaneously operated in parallel or preferably are alternately operated, cleaned and prepared for further operation in order that the coking stage in common with the rest of the system may be operated continuously. Chambers 30 and 30' are provided with suitable drain lines 51 and 51', respectively, controlled by the respective valves 52 and 52' and these lines may also serve as a means of introducing steam, water or any other suitable cooling medium into the chambers after their operation is completed and after they have been isolated from the rest of the system in order to hasten cooling and facilitate the removal of coke therefrom. Vaporous products are withdrawn from coking chambers 30 and 30' through the respective lines 53 and 53', controlled respectively by valves 54 and 54', and are introduced through line 55 into vaporizing chamber 22 wherein any entrained or dissolved tars and similar high boiling materials are removed therefrom and returned together with the other residual liquid conversion products in this zone to the coking chambers for further treatment. Vaporous products supplied to and evolved from the liquid conversion products in chamber 22 are directed therefrom, in the case here illustrated, through line 56 and valve 57 to heat exchanger 58 wherein any entrained particles of heavy liquid and/or high boiling components of the vapors unsuitable as charging stock for either heating coil of the system are condensed by partial cooling accomplished by indirect heat exchange between the vaporous products from chamber 22 and the high boiling fractions of the charging stock and intermediate conversion products of the process, as will be later more fully described. The condensate formed in heat exchanger 58 may be returned therefrom through line 59 and valve 60 to vaporizing chamber 22 and is preferably employed as a refluxing medium in this zone by being passed over suitable baffles or fractionating means (not shown), which may be located within the upper portion of the vaporizing chamber. The vaporous products from chamber 22 remaining uncondensed in heat exchanger 75

58 are directed through line 61 and valve 62 to fractionation in fractionator 63.

The components of the vaporous products supplied to fractionator 63 boiling above the range of the desired final light distillate product of the process are condensed in this zone as reflux condensate which is separated by fractional condensation into selected relatively low boiling and high boiling fractions. The high boiling fractions are withdrawn from the lower portion of the fractionator through line 64 and valve 65 to pump 66 by means of which they are fed through line 67 and thence, all or in part, through line 68, line 69, valve 70, heat exchanger 58, line 71, valve 72 back into line 68 and thence to the two similar sections of the heating coil in furnace 1 for further conversion. A regulated portion or all of the relatively high boiling oils supplied to furnace 1 may, when desired, bypass heat exchanger 58 by means of valve 73 in line 68.

Selected relatively low boiling fractions of the reflux condensate are withdrawn from a suitable intermediate point in fractionator 63, for example, through line 74 and valve 75 and in the case here illustrated are introduced into stripping column 76 wherein they are substantially freed of dissolved or entrained gases and low boiling components within the range of the desired final light distillate product of the process by means of heat supplied to the column in any desired well known manner such as, for example, by passing a suitable heating medium such as steam, hot oil or the like through a closed coil 77 in the lower portion of this zone. Vapors and gases evolved in column 76 are returned through line 78 and valve 79 to fractionator 63. The reboiled side stream is withdrawn from the lower portion of column 76 through line 80 and valve 81 to pump 82 by means of which this material is supplied through line 83 and valve 84 to conversion in the relatively light oil heating coil located within furnace 31, in the manner previously described.

43 Fractionated vapors of the desired end boiling point are withdrawn together with uncondensable gas produced by the operation from the upper portion of fractionator 63 through line 85 and valve 86 and are subjected to condensation and cooling in condenser 87. The resulting distillate and gas passes through line 88 and valve 89 to collection and separation in receiver 90.

Regulated quantities of the distillate collected in receiver 90 may, when desired, be recycled by well known means (not shown) to the upper portion of fractionator 63 to serve as a cooling and refluxing medium in this zone for assisting fractionation of the vapors and to maintain the desired vapor outlet temperature from the fractionator.

Distillate comprising the unstabilized motor fuel product of the process is withdrawn from receiver 90 through line 91 and valve 92 to pump 93 by means of which it is fed through line 94, valve 95, heat exchanger 96, line 97 and valve 98 into stabilizing column 99 wherein it is subjected to stabilization for the purpose of lowering the vapor pressure of the final motor fuel product of the process by means of removing from the distillate any excessive quantities of low boiling fractions and dissolved normally gaseous compounds such as butane, butylene and lower boiling compounds. A portion of the heat required for stabilization of the distillate in column 99 is supplied thereto in heat exchanger 96, as

will be later more fully described, and the unvaporized distillate collecting in the bottom of column 99 is withdrawn therefrom through line 100 and valve 101 to heat exchanger 102 wherein it is subjected to additional heating and reboiling by indirect heat exchange with a regulated portion of the relatively high boiling oil withdrawn from the lower portion of fractionator 63 and supplied to heat exchanger 102 through line 103 and valve 104 whereby it is partially cooled and from which it is directed through line 105 and valve 106 back into fractionator 63 at any desired point or plurality of points in this zone wherein it serves as a cooling and refluxing medium for assisting fractionation of the vapors. The vapors evolved in heat exchanger 102 are directed through line 107 and valve 108 back into stabilizing column 99. The reboiled and stabilized distillate is withdrawn from heat exchanger 102 through line 109 and valve 110 to heat exchanger 96 wherein it is cooled by indirect heat exchange with the distillate supplied from receiver 90 to column 99 and serves to preheat the distillate. The stabilized and partially cooled distillate from heat exchanger 96 may be directed through line 111 and valve 112 to further cooling and storage or to any desired further treatment. The low boiling materials liberated from the distillate in stabilizer 99 are directed from the upper portion of this zone through line 113 and valve 114 and are subjected to cooling and condensation in condenser 115 of any suitable form from which the resulting distillate and gas passes through line 116 and valve 117 to collection and separation in receiver 118. The distillate collected in receiver 118 may be utilized as a cooling and refluxing medium in stabilizer 99 by recirculating the same to the upper portion thereof through line 119, valve 120, pump 121, line 122 and valve 123.

The uncondensed gaseous products are released from receiver 118 through line 124 and valve 125 and are introduced into absorber 126. The gases separated from the unstabilized distillate in receiver 90 are also directed to absorber 126 by means of line 127 and valve 128. The gaseous products of the process thus supplied to absorber 126 are intimately commingled in this zone with regulated quantities of the hydrocarbon oil charging stock for the process which is supplied through line 129 and valve 130 to pump 131 by means of which it is fed through line 132 and valve 133 into the upper portion of the absorber. The remaining portion, if any, of the charging stock may be directed, for example, through line 134 and valve 135 into the lower portion of absorber 126 or, depending primarily upon its characteristics, may be supplied direct to fractionator 63 or to either heating coil of the system by well known means (not shown). The unabsoed components of the gases are released from the upper portion of absorber 126 and pass through line 136 and valve 137 to storage or elsewhere, as desired. The enriched charging stock containing absorbed high boiling components of the gases including propane, butane and the corresponding unsaturated compounds is withdrawn from the lower portion of absorber 126 through line 138 and valve 139 to pump 140 by means of which it is directed through line 141, valve 142 and line 105 into fractionator 63, wherein it is subjected to vaporization and to fractionation together with the vaporous conversion products of the process, the low boiling and high boiling fractions of the charging stock combining with

the corresponding low boiling and high boiling fractions of the reflux condensate to form the relatively low boiling and high boiling oils subjected to conversion in the low boiling and high boiling oil heating coils of the system.

The preferred range of operating conditions which may be employed to accomplish the objects of the present invention in an apparatus of the character illustrated and above described may be approximately as follows:

The temperature employed at the outlet from the heavy oil heating coil may range, for example, from 800 to 950° F., preferably with a superatmospheric pressure at this point in the system of from 100 to 500 pounds, or more, per square inch. The light oil heating coil may employ an outlet conversion temperature ranging, for example, from 900 to 1050° F., preferably with a superatmospheric pressure of from 300 to 800 pounds, or more, per square inch, although lower pressures down to substantially atmospheric may be employed at the outlet from the light oil heating coil, when desired, particularly in case all of the heated products from this zone are introduced into a low pressure coking zone. The reaction chamber is normally operated at a superatmospheric pressure which may range from 100 to 500 pounds, or more, per square inch, which, however, is no greater than that employed in the communicating heating coil utilizing the lowest pressure, in case heated products from both heating coils are introduced into the reaction chamber. The vaporizing chamber is preferably operated at a substantially reduced pressure relative to that employed in the reaction chamber ranging, for example, from 100 pounds, or thereabouts, per square inch, down to substantially atmospheric pressure. Any desired pressure ranging from substantially atmospheric to 150 pounds or more per square inch may be employed in the coking zone although, as previously mentioned, this zone is preferably operated at a somewhat higher pressure than that employed in the vaporizing chamber. The fractionating, condensing and collecting portions of the cracking system may utilize pressures substantially the same or somewhat lower than the pressure employed in the vaporizing chamber. The stabilizing column may be operated at any desired pressure ranging from substantially atmospheric to several hundred pounds per square inch superatmospheric pressure, the preferred range being from 125 to 275 pounds per square inch. The absorber is preferably operated at substantially the same pressure as that employed in the receiver and gas separator of the cracking system, the preferred range being from 50 to 150 pounds per square inch although lower or higher pressures may be employed in this zone, when desired.

As a specific example of one of the many possible operations of the process of the present invention as it may be accomplished in an apparatus of the character illustrated and above described, the charging stock, in this particular case, comprises a gas oil of about 32° A. P. I. gravity which is utilized, in part, as absorber oil in the absorption stage of the system. The enriched absorber oil and the remaining portion of the charging stock is supplied to the fractionator of the system. High boiling components of the reflux condensate and charging stock, 90% or more of which boils above approximately 570° F., is supplied from the fractionator of the system to the heavy oil heating coil through which it flows in two substantially equal streams each of which

are uniformly heated to an outlet conversion temperature of approximately 925° F. at a superatmospheric pressure, measured at the outlet from the heating coil, of approximately 300 pounds per square inch and the heated products are introduced into the reaction chamber of the system which is operated at substantially the same pressure. Both vaporous and liquid conversion products are withdrawn from the lower portion of the reaction chamber and introduced into the vaporizing chamber which is operated at a superatmospheric pressure of approximately 60 pounds per square inch. Non-vaporous residual liquid from the vaporizing chamber is supplied to alternately operated coking chambers maintained at a superatmospheric pressure of approximately 75 pounds per square inch, vaporous products from which are returned to the vaporizing chamber. Low boiling fractions of the reflux condensate and charging stock, 90% or more of which boil within the range of approximately 400 to 600° F. are supplied from the fractionator of the system to the light oil heating coil wherein they are heated to a conversion temperature of approximately 950° F. and then maintained at a substantially constant temperature not exceeding approximately 975° F. being discharged from this zone at a superatmospheric pressure of approximately 750 pounds per square inch. A regulated quantity of the highly heated products from the light oil heating coil sufficient to effect reduction of the high boiling materials in the coking zone to substantially dry coke are supplied to the alternately operated coking chambers and the remainder of these products are introduced into the reaction chamber. The stabilizing stage of the system, which is operated substantially in the manner above described and illustrated, employs a superatmospheric pressure in the stabilizing column of approximately 225 pounds per square inch and the absorber to which gaseous products from the receiver of the cracking system and from the stabilization stage are supplied and therein contacted with the charging stock, as above described, is operated at a superatmospheric pressure of approximately 50 pounds per square inch. This operation may produce, per barrel of charging stock, approximately 70% of 400° F. end point motor fuel having an octane number of approximately 70 by the motor method and a Reid vapor pressure of approximately 10 pounds per square inch and about 50 pounds of low volatile coke of good structural strength and uniform quality, the remainder being chargeable, principally, to lean non-condensable gas.

I claim as my invention:

1. A process for the conversion of hydrocarbon oils which comprises subjecting an oil of relatively high boiling characteristics to conversion conditions of elevated temperature and superatmospheric pressure in a heating coil and communicating reaction chamber, withdrawing both vaporous and liquid conversion products from the reaction chamber in commingled state and introducing the same into a reduced pressure vaporizing chamber wherein separation of vapors and residual liquid conversion products is accomplished, withdrawing the latter from the vaporizing chamber and introducing the same into a coking zone wherein their reduction to substantially dry coke is accomplished, simultaneously subjecting another hydrocarbon oil of relatively low boiling characteristics to independently controlled more severe conversion conditions of elevated temperature, superatmospheric pressure

- and conversion time in a separate heating coil, introducing regulated quantities of the highly heated products from said separate heating coil into the coking zone to assist the coking operation, introducing any remaining portion of the highly heated products from said separate heating coil into the reaction chamber, withdrawing vaporous products from the coking zone and introducing the same into said vaporizing chamber, subjecting vaporous products from the vaporizing chamber to fractionation for the formation of reflux condensate and recovering a light distillate product from the fractionated vapors by condensation.
- 5 15 2. A process of the character defined in claim 1, wherein the reflux condensate formed by said fractionation of the vaporous conversion products is separated into selected relatively low boiling and high boiling fractions which are returned respectively to the relatively light oil and relatively heavy oil heating coils for further conversion.
- 10 20 3. A process of the character defined in claim 1, wherein hydrocarbon oil charging stock for the process is commingled with the vaporous conversion products undergoing said fractionation and the resulting reflux condensate is separated into

selected relatively low boiling and high boiling fractions and wherein said relatively low boiling and high boiling fractions are supplied respectively to the relatively light oil and relatively heavy oil heating coils of the system.

5 10 4. A conversion process which comprises subjecting a relatively heavy hydrocarbon oil to conversion temperature under pressure in a heating coil and communicating reaction zone and subsequently separating the same into vapors and unvaporized oil in a separating zone, removing unvaporized oil from the separating zone and introducing the same to a coking zone, simultaneously passing a lighter hydrocarbon oil through a second heating coil and heating the same therein to higher conversion temperature than the oil in the first-named coil, dividing the resultant heated products from said second coil and introducing to the coking zone a sufficient quantity thereof to reduce the unvaporized oil therein to coke, introducing the remaining portion of said heated products from the second coil into said reaction zone, removing vapors from the coking zone and introducing the same to the separating zone, and fractionating and condensing the vapors from the separating zone.

JOHN B. BARNES.
